UNITED STATES PATENT OFFICE.

SALOMON LEBENSAET, OF CHARLOTTENBURG, GERMANY.

APPARATUS FOR ROLLING UP PAPER OR THE LIKE.

1,302,934.

Specification of Letters Patent.

Patented May 6, 1919.

Application filed April 14, 1915. Serial No. 21,418.

To all whom it may concern:

Be it known that I, SALOMON LEBENSAET, an Austrian citizen, and resident of Charlottenburg, near Berlin, Germany, have invented certain new and useful Improvements in an Apparatus for Rolling Up Paper or the like, of which the following is a specification.

My invention relates to the propulsion and speed regulation of gathering rolls for paper and other material which are driven by an electric motor and it has for its object to provide electrical means for keeping constant the energy supplied to said driving motor, in order to cause a constant pull to be exerted upon the paper or other material as it is wound upon the roll notwithstanding the variation in diameter.

In the manufacture of paper and other sheet materials as well as of cord, wire, etc., gathering rolls are employed to receive the material after it has been finished. It will of course be readily understood that the velocity of the material must be maintained substantially constant and that in consequence thereof, the speed of the gathering roll must be decreased as its diameter is increased during the gathering. Under the practice which has heretofore usually prevailed friction clutches have been interposed between the gathering roll and its shaft which permitted the speed of the roll to decrease by reason of the pull exerted upon it by the material as it is passed onto the roll. It is easy to conceive that the frictional resistance of the clutches frequently caused the paper to be subjected to a considerable part of the pulling energy of the motor driving the roll, the paper being then torn in many cases.

Another means for keeping the velocity of the material constant consisted in an arm or the like resting on the periphery of the material wound upon the roll, the said arm being displaced in accordance with the increase of diameter of the roll and thereby operating a field rheostat or other resistance inserted in the motor circuit in such a manner as to increase or decrease the resistance included in this circuit and thereby to vary the speed of the motor in accordance with the variations of the diameter of the roll, the velocity of the material being thereby maintained constant. In practical use devices of this sort have proved to be cumbersome for the reason that the arm has to

be lifted whenever the roll is being replaced; moreover this device does not follow the variations in diameter of the roll with sufficient accuracy, it being practically impossible to adapt the variations in pull resistance to the rather small variations in diameter for a given length of paper.

According to my present invention the energy of the driving motor of the gathering roll is kept constant and its speed is varied in accordance with the variation in diameter of the roll by means of a power relay inserted in the motor circuit.

The single figure of the accompanying drawing is a diagrammatic view of a system embodying my invention. 1 is a strip or line of paper or other material fed from the last roll 2 of a paper machine, over a plurality of rolls 3 for drying or other purposes, onto a gathering roll 4. The paper machine is driven by an electric motor m^1 and the gathering roll is driven by an electric motor m^2 . Energy is supplied to both these motors by a generator S connected with an exciter e , both rotating at constant speed. A hand switch a inserted in the motor circuit serves to cut the gathering motor m^2 in or out. A power relay w is further inserted in this circuit, the core k of the relay being influenced by a spring f adapted to be adjusted by means of a screw t . Core k is connected to a double pole double-throw switch d serving to connect the exciter e with a small auxiliary motor m^3 serving to actuate the contact lever h of a resistance inserted in the shunt n of the gathering motor m^2 , said shunt being also supplied with current by the exciter e . A regulating resistance g adapted to be varied by hand is further inserted into the circuit of the motor m^2 , said resistance serving for reducing the voltage of the said gathering motor without however altering the speed of the paper machine.

It is clear that by adjusting the relay w by means of screw t in accordance with the mechanical resistance of the paper or the like wound upon the roll, a certain predetermined pull may be exerted upon the paper or other material, the relay effecting an increase of the excitation of the gathering motor as soon as the current strength shows a tendency to increase. This increase of excitation then causes the counter-electromotive force to be raised to such an extent that the current strength remains constant in

spite of the fact that the motor is slowing down. Now, a motor operating with constant current strength at a constant voltage will supply a constant energy which in turn will exert a constant pull upon the paper or other material as the product of the pull exerted on the paper and of its own velocity represents the energy received. In order to adjust the system as a whole to a predetermined uniform velocity of travel and a predetermined uniform pull exerted on the paper, it is only necessary, before starting to wind up the paper, to adjust the relay to a predetermined current value, said value being dependent upon the specific mechanical resistance of the paper.

The novel system can be easily adapted to various requirements of service. Preferably the main driving motor of the paper machine is connected to a current source of adjustable voltage, the gathering roll driving motor being fed from the same source. In case that the special kind of paper requires the paper machine to run at greater speed, according to my invention merely the voltage of the current source has to be increased. The speed of the gathering motor will then automatically increase. The power relay inserted in the armature circuit of the gathering motor will regulate the consumption of current so as to make the pull exerted upon the paper constant.

It is easy to adapt the novel system to existing plants, especially so in view of the fact that the driving motors of paper machines are generally fed from a current source of variable voltage, the Ward Leonard system being frequently used for this purpose. If during service the operator holds it necessary to increase the voltage, he

need only increase the excitation of the generator in order to increase the speed of both driving motors. On the other hand he may cause the gathering motor to run at a slower speed independently from the paper machine or to be stopped altogether.

The relay serving to regulate the speed of the gathering motor may be made to vary the shunt excitation of the terminal voltage, such as in shunt motors, or the rotor resistance, such as in induction motors or it may be used for shifting the brushes in the case of an alternating commutator motor.

I claim:—

1. In combination with a paper machine, a winding roll, separate electric driving motors for said machine and for said roll, a current source of adjustable voltage for feeding both motors with energy and a power relay inserted in the circuit of the roll driving motor.

2. In combination with a paper machine, a winding roll, separate electric driving motors for said machine and for said roll, a current source of adjustable voltage for feeding said motors with energy, a power relay inserted in the circuit of the roll driving motor and means for varying the voltage of said current source.

3. In combination with a paper machine, a winding roll, separate electric driving motors for said machine and said roll, a current source of adjustable voltage for feeding said motors with energy, a power relay inserted in the circuit of the roll driving motor and means for varying the voltage of said roll driving motor.

In testimony whereof I have hereunto set my signature.

SALOMON LEBENSART.
